UNITED STATES PATENT OFFICE.

CHARLES E. HADLEY, OF CHICOPEE, MASSACHUSETTS.

SEWING-MACHINE.

No. 861,276.

Specification of Letters Patent.

Patented July 30, 1907.

Application filed October 9, 1902. Serial No. 126,408.

To all whom it may concern:

Be it known that I, CHARLES E. HADLEY, a citizen of the United States of America, and a resident of Chicopee, in the county of Hampden and State of Massachusetts, have invented certain new and useful Improvements in Sewing-Machines, of which the following is a full, clear, and exact description.

This invention relates to sewing machines, and it has for one of its objects the provision of a machine for uniting the abutting edges of two pieces of fabric, or otherwise sewing a fabric or fabrics by an overstitch formed of two threads, the successive loops of which are interlocked, thus constituting what might be termed "a lock over stitch."

15 Hence my invention comprises as one of its features an eye-pointed needle, mounted for movement transversely of the fabric and in such a manner that the needle-thread is carried through the cloth, and in the combination therewith, of a device whereby the other 20 or interlocking thread is passed through the loops formed by the needle thread at both ends of the needle stroke.

The needle-operating mechanism includes in its preferred organization an oscillatory needle arm, the 25 movement of which, on both sides of the seam line, is such that a loop will be formed in the needle thread immediately upon the initial movement of said arm on its return stroke, in either direction, so that the shuttle or locking thread may be passed through said loops, 30 first on one side and then on the other, successively, thus not only preventing the loops from being drawn out of the fabric, but furthermore, forming a zigzag line across the joint line between the cloth sections, and consequently assisting in drawing, in cases where separate pieces are being sewed, the abutting edges together. While it is obvious that this result may be accomplished in various ways, I have shown the secondary or locking thread wound on a bobbin, which is carried in a shuttle, having both of its ends pointed, so 40 as to pass through the loop, when moving in either direction back and forth, thus passing the shuttle thread entirely through the loop alternately on opposite sides of the cloth joint line, said loop being "drawn in", as soon as the shuttle has passed through, by any suitable 45 tension device coöperative with the needle movement.

My invention has furthermore for its object the provision of a shuttle and its carrier having a predetermined movement and disposed on the same side of the 50 fabric with the needle arm, the paths of the shuttle and needle intersecting each other at two points disposed at opposite sides of the cloth seam line, and in such a manner that the movement of needle on its return stroke will leave a loop of the needle thread in a direct 55 line with the path of the shuttle.

As a convenient organization of the needle and shuttle mechanism for achieving this result, I preferably mount both the needle and the shuttle for oscillation around parallel axes, one of which is superposed relatively to the other, the radial distance of the needle 60 from its oscillation axis being smaller than that of the shuttle from its axis.

From the above it will be understood that the paths of both needle and shuttle are fixed, and inasmuch as the machine is adapted to goods of different thicknesses, 65 the table is mounted for movement to conform to the various requirements, suitable means being provided for forcing the table upward, and thus cause the fabric to come into proper position to be operated upon, this position being governed by a presser foot, which is normally stationary but may be adjusted for different thicknesses of cloth as well as to regulate the penetration depth of the needle, so that the needle thread may appear on both sides of the fabric, or else a "blind stitch" 70 may be made.

In the accompanying drawings, in which similar characters denote similar parts,—Figure 1 is a side view of a machine embodying my invention. Fig. 2 is a top view thereof partly broken away to disclose the interior. Fig. 3 is an end view of the machine looking from the 75 right of Fig. 1. Fig. 4 is a vertical cross section through the table, and illustrates the shuttle carrier and shuttle in detail. Fig. 5 is a front view of the shuttle carrier removed from the machine in its operating mechanism. Fig. 6 is a side view thereof looking from the left of Fig. 80 5. Fig. 7 is a front view of the shuttle race. Fig. 8 is a transverse section thereof, on line 8—8, of Fig. 7. Fig. 9 is a central section of the eccentric for operating the feed mechanism. Fig. 10 is a front view thereof looking from the right of Fig. 9, and Figs. 11 to 18 inclusive 85 are perspective views illustrating the stitch as it is progressively formed by the movement of the shuttle and needle.

Referring to the drawings, 20 denotes a suitable frame having bearings 21, 22, for supporting the main driving 90 member or shaft 23, on which the several actuating devices of the machine are mounted and which may be operated from a band wheel 24 in any convenient manner.

The needle N is in the present instance, secured to an arm 25 mounted upon a needle shaft 26, which is 95 journaled in the frame 20 and is provided near its rear end with an arm 27 connected and operated for oscillation by an eccentric 28 secured upon the main shaft 23 above mentioned. In this manner the needle has imparted to it an oscillatory movement in a predetermined path relative to the needle N so as to conform to the various thicknesses of material to be sewed.

The presser foot, which is herein designated by P, is normally stationary during the operation of sewing, but is adapted for vertical adjustment relatively to the nee- 110

dle path so that the position of the cloth to be sewed may be varied to permit the needle to penetrate the cloth at a higher or lower point thereof, and thus produce either a blind stitch or one in which the needle 5 thread will appear on both sides of the cloth as will be hereinafter described.

The adjustment of the presser foot may be accomplished in any suitable manner, and in the present instance I have mounted the same for sliding movement 10 in the frame 20; while a screw 29 rotatably held in a bracket 30 may be employed for adjusting the presser foot as desired.

While from this construction it will be understood that the upper side of the cloth will be substantially in a 15 predetermined position relative to the needle, the table is as has been above mentioned, mounted for movement relative thereto, it being preferably provided with an arm 31, the rear end of which may be pivotally supported, as at 32, on the frame; while a direct support is 20 afforded to the table by a spring 33 interposed between the head 34 of a bolt 35 and a washer 36 through which said bolt may loosely pass and which in turn is supported by a projection 37 provided therefor on the frame 20.

The upward movement of the table may be limited, 25 as for instance, by a nut 38 in screw-threaded engagement with the bolt 35 and adapted to come into contact with the lower surface of the projection 37 above referred to.

As previously stated, the present machine is especially designed for the production of a lock stitch, and for this reason the needle thread is co-operative with a lock thread preferably carried in a shuttle S, the movement of which is such as to intersect the path of the needle point near both ends of its movement, and which 35 may be supported in a carrier, designated in a general way by C and mounted for oscillation around an axis not in alinement with the needle shaft 26 and preferably superposed thereto.

The carrier C is provided with pins 40 exteriorly en- 40 gaging the shuttle near both ends thereof, but allowing free play thereto in order to allow the thread, or more particularly speaking the loop of the needle thread to slip over said shuttle, as is usual in lock stitch machines.

The operation of the carrier C depends upon the ac- 45 tion of a shaft 41 constituting its actuating member and journaled in suitable bearings in the frame 20. Oscillatory movement may be imparted to the shaft 41 by an arm 42 mounted upon a shaft 41 and connected with an eccentric 43 secured upon the main shaft 23.

From this construction it will be seen that the move- 50 ment of the shuttle is predetermined, and that on account of the non-alinement of the two axes of oscillation, the paths of the shuttle and needle will intersect each other at opposite sides of a line passing through 55 both of the centers of said shafts; this line being in a plane with the joint line of the cloth pieces to be sewed together and supported on the table T, the cross section of which is substantially inverted V-shaped and clearly shown in Figs. 3 and 4, so that their edges may abut in 60 proper position relative to the movement of the needle and shuttle.

As above stated, the shuttle S is supported in a car- 65 rier C, and inasmuch as the pins 40 of the carrier are only functional in causing the shuttle to move in unison with the carrier, means are provided whereby said shut-

tle will be held in proper engagement with and between the pins 40; these means consisting substantially of a plate 44 disposed in front of the shuttle and constituting a protection and a race-way for the shuttle.

The plate 44 is preferably made L-shaped in section, 70 to afford a bearing member 45 for the carrier C, the construction of which is necessarily light and which is provided with grooved lugs 46 to straddle the rib portion 45 of the shuttle race.

The plate 44 is preferably stationary and secured to 75 the arms 47 of a support member 48 clamped on a projecting hub on the frame 20, as for instance, by a screw 49.

The feed mechanism, which I preferably employ in connection with my present machine, is clearly illustrated in Figs. 1, 3 and 4 of the drawings, and comprises 80 a feed dog 50 the cloth-engaging teeth of which have a vertical as well as a longitudinal movement relative to the stationary presser foot P.

The longitudinal movement of the feed dog is in the present instance, dependent upon the movement of a 85 slide 51 on which said feed dog is pivotally supported, as at 52, and which is guided by a bracket 53 secured upon the under side of the table T, as for instance, by a screw 54.

Reciprocatory movement is imparted to the slide 51 90 by a lever 55 constituting a link between said slide and an actuating member consisting substantially of an eccentric 56 mounted upon the shaft 23 and comprising a cylindrical member 57 the axis of which is disposed at an angle with that of the driving shaft 23 as clearly shown 95 in Fig. 1. The cylindrical member 57 is fast to, and driven by, the driving-shaft. Surrounding part 57 is a sleeve 58 loosely fitted for free rotation, relatively thereto. The periphery of sleeve 58 is spherical so as to allow a manner of universal joint action. 100

59 is a case having a socket into which the spherical sleeve 58 is fitted to freely move and which carries a spline preventing the sphere from revolving in the case, see Figs. 9 and 10.

On the exterior of the socketed case are provided 105 ways to allow the approximately vertical adjustment of the yoke 65 which is fastened by set screws 75, Figs. 1 and 10, which adjustment regulates the throw of the feed dog 50.

As the distance of pin 66 from center of driving shaft 110 23 is increased, it will be seen that the wobbling effect will be correspondingly increased. As the only motions which this wobbling eccentric is called upon to perform are a reciprocatory vertical, and a horizontal reciprocatory motion, the lateral throw of the eccentric 115 is neutralized or rendered non-effective by the provision of duplicate studs 66 66 fast to the yoke 65 and free to slide in the ends of the bifurcated or bowed part 55. Thus the lever has a movement in a vertical plane imparted thereto from a shaft parallel therewith by 120 the interposition of the wobbling eccentric device just above described which movement of the lever is approximately a motion in which the longitudinal and vertical effects are properly alternated to give the required motions to the feed dog. 125

The strap 65 of the eccentric carries one end of the link 55, which is pivoted thereto at 66; while the other end of said link is preferably secured to the free end of an arm 67 normally rigid on the slide 51, but adapted for adjustment, as for instance by a screw 68, so as to 130

vary the position of the slide relatively to the actuating point 66, and in this manner controlling the working position of longitudinal movement of the feed dog 50 as will be readily understood.

5 Since the strap 65 imparts a vertical movement to the point 66, as well as a longitudinal movement, the link 55 is provided with an extension 55' in order to take advantage of this movement for operating the feed dog in a vertical plane and in the required manner; the end 10 of the extension 55' being connected by a link 69 with the rearward extension 50' of the feed dog 50.

Means are provided whereby the working position or vertical movement of said feed dog may be varied so as to take a firmer or looser hold upon the under side of 15 the material to be sewed, and for this reason, the link 69 is slotted as shown at 69' to permit the dog 50 to be adjusted in a vertical plane without in any way altering the amount of vertical movement thereof, during its regular operation.

20 As previously stated, the machine is especially designed for an over lock stitch such as is for instance illustrated in Figs. 11 to 18, inclusive, of the drawings. In these figures, Fig. 11 shows the needle after it has passed the needle thread through the cloth and has 25 just commenced on its return stroke, the shuttle being in position to carry the needle thread *t* through the loop *L* which is formed in the needle thread *N* by the needle during its backward stroke at the right hand side of the cloth joint line *J*; in Fig. 12 the needle thread 30 *N* is shown as having its loop surrounding the shuttle; while in Fig. 13 the shuttle is illustrated as having passed through the loop *L* and the needle is just about to complete its return stroke thus "drawing in" said loop and binding the shuttle thread *t* in place. In 35 Fig. 14, the needle has commenced its forward stroke, and the shuttle is about to pass through the loop *L'* formed by the slackening of the thread *n* while in Fig. 15, the shuttle thread *t* has been drawn through said

loop *L'*, and the shuttle is about to finish its return stroke, thus leaving the shuttle thread *t* between the 40 needle thread *n* and the upper surface of the cloth. In Fig. 16 the needle is shown in position corresponding substantially to that of Fig. 12, having left a loop on the right hand side of the cloth joint line to permit the shuttle thread to be carried therethrough, which condition 45 is shown in Fig. 17, so that the stitch line as really completed, will have an appearance like that shown in Fig. 18, in which it is clearly shown that the shuttle thread is entirely on one side of the cloth and forms a zig-zag line between the loops formed in the needle 50 thread at opposite sides of the cloth joint line.

It is, of course, obvious that the shuttle thread may be drawn through the cloth at the right hand of the cloth joint line provided the tension of the needle thread is sufficient to produce this result. 55

Having described my invention, what I claim as new and desire to secure by Letters Patent is:—

1. The combination, with a table, a needle, and means for oscillating said needle relatively to said table, of a shuttle pointed at both ends, a shuttle-carrier having pins for loosely engaging said shuttle, a stationary race having an **L** shaped cross section and for guiding said shuttle in a path to intersect the needle-path at both ends of its travel, and means for oscillating said shuttle-carrier. 60

2. The combination, with a table, a needle, and means for oscillating said needle relatively to, and on an axis above, said table, of a shuttle, pointed at both ends, a shuttle-carrier having pins for loosely engaging said shuttle, means for oscillating said carrier on an axis offset from, and parallel with, said needle axis, and an arc shaped 70 shuttle-race having an **L** shaped cross section, for guiding said shuttle in a path substantially concentric with the center of oscillation of the carrier.

Signed by me at Springfield, Massachusetts, in the presence of two subscribing witnesses.

CHARLES E. HADLEY.
